FREDERICK LUX, OF WATERBURY, CONNECTICUT, ASSIGNOR TO THE LUX CLOCK MANUFACTURING COMPANY, OF WATERBURY, CONNECTICUT, A CORPORATION OF CONNECTICUT

INTERVAL TIMER

Application filed October 6, 1928. Serial No. 310,832.

This invention relates to time-controlled apparatus, and more particularly to an interval timer adapted to operate a switch mechanism after the expiration of a predetermined period of time.

One object of this invention is to provide an interval timer having an indicating pointer which may be turned backwardly in case it may have been set to operate at a greater time interval than desired.

A further object is to provide a device of this nature which will be simple in construction, inexpensive to manufacture, easy to manipulate, compact, ornamental in appearance, and very efficient and durable in use.

With these and other objects in view there has been illustrated on the accompanying drawings one form in which the invention may be conveniently embodied in practice.

20 Fig. 1 represents a front view of the interval timer and switch mechanism.

Fig. 2 is a side sectional view of the same, taken along the line 2—2 of Fig. 1, looking in the direction of the arrows.

25 Fig. 3 is a front sectional view, taken along the line 3—3 of Fig. 2, looking in the direction of the arrows.

Fig. 4 is a rear sectional view of the interval timer as it appears when the back plate 20 has been removed.

Referring now to the drawings in which like reference numerals denote corresponding parts throughout the several views, the numeral 10 indicates a vertical back plate adapted to be attached to a wall or any other suitable location. The back plate 10 has a plurality of horizontal posts 11 (four in this instance) extending therefrom for supporting a pair of front and rear "clock-work" plates 12 and 13, respectively.

40 The "clock work" or spring motor is located between the plates 12 and 13 and is driven by a spiral main spring 14 connected at its inner end to a main shaft 15. The main shaft 15 is 45 journaled in the plates 12 and 13 and is reduced in diameter at its forward end 16. The end 16 extends forwardly through the plate 12 and is squared at 17 for non-rotatively receiving an indicating pointer 18 detachably secured in position, as by a nut 19

threaded on the extremity thereof. The clock-work is adapted to be governed by the usual standard form of balance wheel 20 and escapement mechanism 21.

The indicating pointer 18 is located in front of a dial 22 having suitable time indicating indicia marked thereon, preferably being graduated in the minutes of an hour. The dial 22 is mounted on a base 22a supported in position by a plurality of short posts 23, said posts being connected at their rear ends to the plate 12. The indicating pointer 18 is provided with a pair of forwardly extending handles 24 and 25 to facilitate its operation, and in order to prevent the pointer 18 from being rotated more than one revolution, the dial 22 has a stop member 26 projecting forwardly therefrom at a point just to the left of the minute graduation marked "60".

In order to permit the pointer 18 to be turned backwardly in case it has been moved beyond the desired point, provision is made of a pair of resilient contacting flared metal discs 27 and 28. The disc 27 lies in contact with a washer 29 slidably and non-rotatively mounted on the main shaft 15. The washer 29 frictionally engages a ratchet 29a connected as by pawls 30a to a main gear 30. The gear 30 transmits the power of the main spring 14 to the clock train 31 and said pawls 30a are adapted to yield to permit the winding of the main spring 14 by the operation of setting the indicating pointer 18 to the time interval desired.

By means of this construction it will be seen that the handle 18 may be readily turned back to the zero point or any intermediate point for unwinding the main spring 14 the desired amount, thereby shortening the interval for which the timer is set, the washer 29 and ratchet 29a being adapted to slip over one another during this movement.

In the embodiment of the invention herein illustrated, the running down of the "clock work" mechanism is adapted to actuate a switch, preferably of the two pole toggle type and mounted in a casing 32 located on the back plate 10 near the bottom thereof. The

switch has suitable binding posts 33 and 34 located outside of the casing 32.

The switch is opened and closed by an operating lever 35 which projects up through the 5 top of the casing, said lever 35 having a pair of arms 36 and 37, said arms being connected by a bridging pin 38. The ends of the pin 38 have button members 39 located outside of said switch arms 36 and 37, said 10 buttons serving to receive a pair of helical springs 40 which have their other ends connected to a pin 41 mounted upon the base 10.

By means of this construction it will be seen that the springs 40 will normally tend 15 to pull the switch operating lever 35 to the left into the "off" position shown in Fig. 3. The switch lever 35, however, is adapted to be held in the "on" position shown in Fig. 4, by means of a detent arm 42 pivoted on a 20 pin 43, and normally urged in a counterclockwise direction by a wire spring 44. Intermediate its ends the detent arm 42 is provided in its lower edge with a rectangular slot 45 which is adapted to drop down over 25 the central portion of the bridging pin 38 of the switch operating lever 35 whenever the indicating pointer 18 has been turned beyond a certain definite arc, in this instance somewhat less than 60 degrees, or about 9 minutes 30 on the graduated minute scale of the clock dial.

Shortly before the pointer 18 has reached this point, the switch lever 35 will be snapped rapidly from the "off" position of Fig. 3 to 35 the "on" position in Fig. 4 by mechanism now to be described. The main shaft 15 has a depending movement arm 46 rigidly secured thereto as by a nut 47, said movement arm having a pin 48 at its free end located in 40 alinement with a rockable fork member 49 pivoted upon a stud shaft 50 frictionally journaled in the plates 12 and 13.

In operation, the turning of the indicating pointer 18 as above described will rock the 45 fork member 49 and carry with it a depending switch actuating member 51 carried by said stud shaft and having a cam edge 52 adapted to engage the central portion of the pin 38, forcing it to the right from the position shown in Fig. 3 to that shown in Fig. 4. During this operation, the pin 38 will ride under the edge of the detent arm 42 until it is engaged by the notch 45 therein. After the timer has been set to the desired interval, the pointer will be released, and as the main spring 14 runs down, the pointer will be turned in a counterclockwise direction carrying the movement arm 46 with it. The pin 48 carried by said arm 50 46 by reason of its location between the teeth of the fork member 49 will force the fork in a clock-wise direction, causing the switch actuating member 51 to move in clockwise direction striking a pin 53 on the upper end of the detent member 42 and lifting 65

said detent member until its slot 45 becomes disengaged from the pin 38, whereupon the springs 40 will suddenly pull the switch lever 35 to the left into the position shown in Fig. 3.

The interval timer herein disclosed is adapted for use in switching the current on and off of various types of current consuming devices, such as electric cookers, water heaters, violet ray apparatus, washing machines, permanent wave machines, etc.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a time-controlled mechanism, a switch-actuating lever, a constant-speed motor having a rotary lug, a lever-actuating member having a fork fitting about said lug, a spring for urging said lever to one circuit controlling position, a detent arm to hold said lever in the other circuit controlling position, and a pin on said detent arm in alinement with said member for causing said lever to be released after a predetermined interval of time, said member being adapted to be manually rotated in one direction to move said lever to said other circuit controlling position and to be automatically rotated in the reverse direction by said motor to release said detent arm.

2. In a time-controlled mechanism, a switch-actuating lever, a constant-speed motor having a rotary lug, a lever-actuating member having a fork fitting about said lug, said member being mounted on a stud shaft below the main shaft of said motor, a spring for urging said lever to one circuit-controlling position, a detent arm to hold said lever in the other circuit controlling position, and a pin on said detent arm in alinement with said member for causing said lever to be released after a predetermined interval of time, said member being adapted to be manually rotated in one direction to move said lever to said other circuit controlling position, and to be automatically rotated in the reverse direction by said motor to release said detent arm.

3. In a time-controlled mechanism, a switch-actuating lever, a constant-speed motor, a lever-actuating member rotatively connected with said motor, a spring for urging said lever to one circuit controlling position, a detent arm having a notch in its

lower edge to hold said lever in the other circuit controlling position, and a pin on said detent arm in alinement with said member for causing said lever to be released after a 5 predetermined interval of time, said member being adapted to be manually rotated in one direction to move said lever to said other position and to be automatically rotated in the reverse direction by said motor to release said 10 detent arm.

In testimony whereof, I have affixed my signature to this specification.

FREDERICK LUX.
